United States Patent

Des. 239,474
Patented Apr. 6, 1976

239,474

SIGN

Peter De Korte, 329 Calvin Court,
Wyckoff, N.J. 07481

Filed Nov. 12, 1974, Ser. No. 523,150

Term of patent 14 years

Int. Cl. D20—02

U.S. Cl. D96—12 R

FIG. 1

FIG. 2

FIG. 3

FIG. 4

FIG. 5

FIG. 1 is a perspective view of a sign showing my new design;

FIG. 2 is a top plan view thereof;

FIG. 3 is a bottom plan view thereof;

FIG. 4 is an elevational view thereof from the side opposite from FIG. 1; and

FIG. 5 is an elevational view from the edge.

The indicia is shown in broken lines in FIGS. 1 and 4 for illustrative purposes only.

I claim:

The ornamental design for a sign, substantially as shown and described.
